PAPER ARTICLE OF HEAD WEAR

William J. Long, Delaware, Ohio, assignor to White Castle System, Inc., Columbus, Ohio, a corporation of Delaware

Application May 2, 1952, Serial No. 285,644

3 Claims. (Cl. 2—198)

This invention relates to articles of head wear, particularly articles adapted for feminine use and by those engaged in various occupations, such as waitresses, nurses, housemaids and others.

It is an object of the invention to provide an article of head wear for the general purpose stated, in which the article is formed entirely, in so far as the body thereof is concerned, from paper or other similar relatively inexpensive flexible material, whereby following certain periods of use of the article, the same may be economically discarded and a new article substituted therefor, thus avoiding laundering or other renovation of the article.

Another object of the invention is to provide a paper cap, or other similar article, which constitutes an improvement upon the construction disclosed in my prior application, Serial No. 271,789, filed February 15, 1952.

In the cap articles disclosed in my aforesaid patent application, the articles are adapted to be secured to the head of the wearers thereof by means of elastic bands, the latter being so arranged that the ends thereof are fastened to the articles, so that when the latter are positioned on the wearer's head, the bands may be tensioned about the back of the wearer's head to hold the articles in place. It has been found that the use of the elastic bands is objectionable to many wearers. Users of the articles have discovered that the elastic bands, tapes, or straps used in holding the articles in place tend to interfere with and disarrange the style and appearance of the wearer's hair. Also, the elastic devices are considered objectionable by different users because of the pressures which they apply when stretched about the wearer's head.

It is the purpose of the present invention to provide a paper cap or article of head wear which while adequately fulfilling the purposes for which it is adapted to be used is so formed that it may be retained in place by a U-shaped hoop-like securing member, normally concealed in the folds of the article, the construction and mounting of the device enables the same to apply sufficient pressure to the head of the wearer to retain the device in its operative position and yet will avoid disarranging the wearer's hair or causing physical discomfort.

A still further object of the invention is to provide a novel securing means for paper articles of head wear which may be readily inserted into or removed from an associated article, permitting the fastening appliance to be used repeatedly for successive articles as the latter are worn and minimizing expense in the use thereof.

For a further understanding of the invention, reference is to be had to the following description and the accompanying drawings, wherein:

Fig. 1 is a plan view of the blank from which the article of head wear comprising the present invention is formed;

Fig. 2 is a vertical longitudinal sectional view taken through the article disclosing the same in its finally folded form and adapted for use. In this figure, the hoop-like attaching member is shown in cross section in its operative position in the article.

2

Fig. 3 is a vertical sectional view taken on the line 3—3 of Fig. 2;

Fig. 4 is a fragmentary elevational view looking toward one of the lower inside corners of the article and showing 5 a modified form of pocket for the reception of the removable ends of the fastening hoop;

Fig. 5 is a perspective view disclosing a further modified form of the invention;

Fig. 6 is a vertical longitudinal sectional view taken 10 through the article illustrated in Fig. 5;

Fig. 7 is a detail perspective view of one of the hoop-like fastening members employed in connection with the articles of head wear.

Referring more particularly to the drawings, and especially 15 to the form of my invention disclosed in Figs. 1 through 3, my improved article of head wear is die cut, or otherwise formed, from a single blank of sheet material, such as paper, paperboard, synthetic resins or the like, to produce a flexible body.

20 The body is formed to provide a head-embracing crown band 1, the latter being adapted for arcuate curvature over the head of the wearer, with the sides 2—2 of the band disposed for engagement with the sides of the wearer's head. Also formed integrally with the band 1 is a 25 positioning flap 3, which is placed so that it surrounds, or presses upon the top of the wearer's head. The top portion shown at 1a of the crown band, and the flap 3, extend upwardly and angularly with respect to the horizontal from the forwardly located edge 4 which forms the 30 juncture between the part 1a and the flap 3.

In this instance, the flap 3 is formed centrally thereof with a pair of transversely spaced parallel slits 5, which form between them a web shown at 6. Adapted to be inserted through the slits 5 and to underlie the web 6 is 35 the intermediate portion of a hoop-like resilient fastening member 7. This member is arranged interiorly of the article of head wear and is concealed thereby from exterior view. Preferably the fastening member is formed from a resilient material, such as one of the synthetic 40 resins, although other materials may be used. By being inserted beneath the web 6 and extending through the slits 5, longitudinal movement of the fastening member of an accidental nature relative to the body of the article is prevented, although no difficulty is encountered in training 45 the hoop through the slits and beneath the web 6.

When so operatively positioned, the hoop serves to hold the article in its proper place. The sides of the fastening hoop closely engage the inner surfaces of the crown band sides 2. In order to confine the ends of the hoop, the 50 sides 2 of the band 1 terminate in tabs 8. These tabs are adapted to be folded about the lines 9 so that the same are disposed on the inside of the article, as illustrated in Figs. 2 and 3. Each of the tabs 8 is formed with a transverse slit 10, which is adapted to register with the slits 11 shown 55 as formed in the lower portions of each of the sides 2. In addition to the slit 11, the lower end of each of the sides 2 is formed with another parallel slit 12.

When the tabs are turned upwardly, as shown in Figs. 2 and 3, the slits 10 and 11 are in registering order. This 60 permits the ends of the positioning and fastening hoop 7 to pass through the registering slits 10 and 11 from the inside of the article to the outside thereof, as shown more particularly in Fig. 5, and the extreme lower ends of the hoop are then inserted in the lowermost of the slits 12, being confined in a pocket 13 formed in the extreme lower portions of the article between the sides 2 and the upturned tabs 8.

In the use of the article, it is a very simple matter to fold the paper blank from which the article is formed by bending the flap 3 inwardly so that it is disposed below the top portion 1a of the crown band 1, and to bend the tabs 8 upwardly so that the slit 10 in each thereof registers

with the body slit 11 of the article. The securing hoop or member then has the intermediate portion thereof inserted beneath the web 6 by being passed through the slits 5 of the flaps 3, and the ends of the hoop or securing member are then trained through the slits 10, 11, and 12 so that the same are disposed in and protected by the materials forming the pockets 13. Due to the resiliency of the hoop or fastening member the sides thereof may be spread apart as the article is positioned upon the head of the wearer. Upon releasing the spread-apart sides, the same respond to the inherent resiliency of the material from which they are formed and engage the sides of the wearer's head with sufficient firmness to positively retain the associated article in its applied position.

This construction avoids the necessity of employing elastic bands or tapes in the securing of such articles as set forth in my aforesaid application, eliminating the objections to the elastic fastening elements and on its own behalf providing a simple, efficient and concealed fastening means which does not disarrange the hair of the wearer nor cause any binding or cutting action, as is apt to occur when elastic bands comprise the fastening means. The hoop may be readily inserted in the paper articles or removed therefrom, so that it may be used repeatedly, thus minimizing the cost of utilizing paper articles of head wear as contemplated herein.

The articles shown in Figs. 5 and 6 possess substantially the same features of construction as that illustrated in Figs. 1 to 3, with the exception that the web 6 has been omitted. While this arrangement positions the central portion of the hoop between the part 1a of the crown band and the flap 3, the latter is allowed to assume an operating position more closely approximating the plane of the wearer's head, as will be apparent by reference to Figs. 2 and 6. In the modification disclosed in Fig. 4, in lieu of employing the slits 10, 11 and 12, the tab 8a is merely folded upon the sides of the crown band and adhesively secured thereto, leaving a pocket as disclosed at 13a in which the lower ends of the hoop 7 are removably received.

It will be noted that in both forms of my invention, the part 1a of the crown band projects upwardly at an angle. In use, suitable indicia is adapted to be printed or otherwise applied on this upstanding portion of the article, such as the name of the commercial establishment in which the article is worn.

In view of the foregoing, it is believed that the construction and advantages of my improved article of head wear will be readily understood by those skilled in the art, and therefore a more extended explanation has been accordingly omitted.

I claim:

1. An article of head wear comprising: a disposable band of freely flexible sheet material, said band being

formed to possess a generally arched formation providing a crown flap and an internal, laterally offset continuation constituting a positioning flap, the latter being integrally joined with inner intermediately disposed edge regions of the crown flap by a fold line which terminates at the opposite ends thereof in outwardly diverging slits separating the crown and positioning flaps at the ends of the latter and enabling the article when folded for use to extend across the top of the wearer's head and downwardly against its opposite sides, the article being open at its front and back, with the positioning flap folded inwardly of the article beneath and within the confines of the crown flap, said crown flap terminating at its opposite ends in inwardly foldable tab regions, the latter being provided with pocket-forming slits adapted for registry with corresponding slits formed in the ends of the crown flap when the tab regions are inwardly folded against the ends of the crown flap; and a bowed, head-engaging and clamping strip having resiliently separable legs, said strip being separable from said disposable article for repeated usage in connection with other substituted articles and being formed so that when applied to a given article the same is disposed between said crown and positioning flaps, with the lower ends of the separable legs of the strip engaged with said slits and held against displacement by the same, whereby to cause said strip to apply inwardly directed forces to the article in resiliently clamping the same on the wearer's head.

2. An article of head wear as defined in and by claim 1, wherein said positioning flap is formed intermediately thereof with web-forming slits for the reception of the intermediate part of said bowed clamping strip in positively retaining said intermediate part of the strip against displacement with respect to the crown flap and the positioning flap between which the strip is disposed.

3. An article of head wear as defined in and by claim 2, wherein the intermediate region of the band-like body of the article is formed with a pair of spaced, parallel, web-producing slits for the reception of contiguous intermediate portions of said clamping strip, whereby to preclude displacement of the strip relative to the article body with which it is joined.
